UNITED STATES PATENT OFFICE.

FRANK W. BOGNAR, OF WILLIAMSPORT, PENNSYLVANIA.

GARMENT-STRETCHER.

1,072,690.

Specification of Letters Patent.

Patented Sept. 9, 1913.

Application filed September 23, 1910. Serial No. 583,468.

To all whom it may concern:

Be it known that I, FRANK W. BOGNAR, a citizen of the United States, residing at Williamsport, in the county of Lycoming, State of Pennsylvania, have invented certain new and useful Improvements in Garment-Stretchers; and I do hereby declare the following to be a full, clear, and exact description of the invention, such as will enable others skilled in the art to which it appertains to make and use the same.

This invention relates to garment stretchers.

The object of the invention resides in the provision of a device of the character named which will be simple in construction, efficient in use, and easy of operation.

A further object of the invention resides in the provision of a garment stretcher which may be easily adjusted so as to be operable in connection with trousers of different lengths and in which the separate leg stretching elements of the device may be adjusted toward and away from each other.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views; and in which—

Figure 1, is a side elevation of the device with the stretching bars in closed or collapsed position; Fig. 2, a side elevation of the device showing the stretching bars in full lines in the position they would occupy just previous to their insertion in a trouser leg, and in dotted lines in the position they would occupy after said stretcher bars have been inserted in the trouser legs and operated to stretching position. Fig. 3, a front elevation of the device with the leg sections thereof shown in full lines in closed or contracted position, and in dotted lines in expanded position; Fig. 4, a plan view of the device; and Fig. 5, a section on the line 5—5 of Fig. 4.

Referring to the drawings the device is shown as comprising a head A. This head is formed of a central block 10 which has secured to its front and rear faces plates 11 and 12; said plates extending at each end

beyond the ends of the block 10. Journaled between the extending ends of the plates 11 and 12 are rollers 13 and 14. Rotatably mounted in each of the rollers 13 and 14 is a threaded stem 15 which has fixed on its upper end a thumb piece 16 whereby said stem may be conveniently rotated. The rollers 13 and 14 are each recessed as at 17 on their lower sides around the stem 15 and in this recess is disposed one end of a tubular member 18 and through which latter the threaded stem 15 projects. Telescoping within the outer end of the tubular member 18 is a second tubular member 19, the inner end of whose bore is threaded and in engagement with the threaded stem 15. By this construction it will be apparent that as the threaded stem 15 is rotated in one direction the tubular member 19 will be moved into the tubular member 18, while a reverse rotation of the stem 15 will move the tubular member 19 out of the tubular member 18.

Mounted on each of the tubular members 18 in a fixed manner, is a collar 20 while a sleeve 21 is slidably mounted on each of the tubular members 19. Pivotedly connected to each of the collars 20 at diametrically opposite points are the ends of toggle levers 22 and 23, while toggle levers 24 and 25 have one of their ends pivotally connected to the sleeve 21 at diametrically opposite points in the latter. Pivoted to each of the toggle levers 22 and 24 at their free ends are stretcher bars 26 which taper toward their outer edges. Likewise pivoted to the free ends of the toggle levers 23 and 25 are stretcher bars 27 which also taper toward their outer edges. Each of the tubular members 19 is provided at its outer end with a flange 28 and seated upon this flange and encircling said tubular member is a spring 29. A ring 30 is slidably mounted upon each tubular member 19 and rests upon the spring 29.

In order to institute the use of the device the sleeves 21 are moved from the position shown in Fig. 1 to the position shown in full lines in Fig. 2. This, as will be apparent, will move the bars 26 and 27 away from the tubular members 18 and 19 and dispose the sleeves 21 against the rings 30 and resiliently support said sleeves upon the springs 29. When in this position the leg sections of the device are inserted in the respective legs of the trousers and pushed smartly therein. When the leg sections are

thus disposed the threaded stems 15 are rotated through the medium of respective thumb pieces 16 so as to draw the tubular members 19 inwardly of respective tubular members 18. During this movement of the tubular members 19 the springs 29 will be compressed and strive to force the sleeves 21 upwardly on respective tubular members 19 and thus expand the bars 26 and 27 so as to effect the desired stretching of the trousers legs. It will of course be noted that the farther into the tubular members 18 the tubular members 19 move, the greater the stretching force exerted upon the bars 26 and 27 by the spring 29. In order to move the leg sections of the device toward and away from each other a handle 31 is rotatably mounted in the block 10 and is provided with a threaded extension 32 disposed between the tubular members 18. Fixed on the extension 32 and engaging the lower side of the block 10 is a nut 32' whereby said extension is held against disengagement from the block. Threaded on the threaded extension 32 is a collar 33 which has pivoted thereto at diametrically opposite points toggle levers 34 and 35. On the outer end of one of the tubular members 18 is fixed a collar 36 to which is pivotally connected the toggle lever 35 while on the outer end of the other tubular member 18 is fixed a collar 37 which is pivotally connected with the toggle lever 34. By this construction it will be apparent that as handle 31 is rotated in one direction the leg sections of the device will be moved away from each other while a reversed rotation of said handle will move said leg sections toward each other.

40 What I claim is:

1. A garment stretcher comprising a head provided with a rotatable handle, a rotatable member carried by said head at each end, a rod supported by each rotatable member for movement therewith, a threaded extension on said handle disposed between said rods, a threaded collar mounted on said extension, a toggle lever connecting said collar with each of said rods whereby the rotation 45 of the handle will move said rods toward and away from each other, and a pair of

stretcher bars connected to each of said rods on opposite sides thereof respectively and adapted for movement toward and away from the rods.

55

2. A garment stretcher comprising a head provided with a handle, a pair of rods supported by said head, means for moving said rods toward and away from each other, a collar fixed to each of said rods at their upper ends, a sleeve slidably mounted upon each of said rods below said collar, a stretcher bar disposed on opposite sides of each rod, and toggle levers connecting each of said bars to said collar and to said sleeve. 60

65

3. A garment stretcher comprising a head provided with a handle, a pair of rods supported by said head, each of said rods comprising a tubular upper member, a tubular lower member telescoping within said upper member and having the upper end of its bore threaded, a threaded stem extending through the upper tubular member and engaging the threaded upper end of the lower tubular member whereby the rotation of 70 said stem will move the lower tubular member into and out of the upper tubular member, a stretcher bar mounted on opposite sides of each of said rods, and toggle levers connecting said bars to the upper and lower 75 tubular members of said rods respectively. 80

85

4. A garment stretcher comprising a head provided with a handle, a pair of rods supported by said head, means for moving said rods toward and away from each other, a collar fixed to each of said rods at their upper ends, a sleeve slidably mounted upon each of said rods below said collar, a stretcher bar disposed on opposite sides of each rod, toggle levers connecting each of 90 said stretcher bars to said collar and to said sleeve, a flange on the lower end of each rod, and a spring encircling each rod at the lower end and having one end in engagement with said flange and its other end adapted to be 95 engaged by said sleeve.

95

In testimony whereof, I affix my signature, in presence of two witnesses.

FRANK W. BOGNAR.
